UNITED STATES PATENT OFFICE

153,341

DESIGN FOR A LOCK OR LATCH CASING

William R. Ferry, Regina, Saskatchewan, Canada

Application May 19, 1947, Serial No. 139,137

Term of patent 14 years

(Cl. D50—5)

To all whom it may concern:

Be it known that I, William R. Ferry, a citizen of Canada, residing in the city of Regina, Province of Saskatchewan, Dominion of Canada, have invented a new, original, and ornamental Design for a Lock or Latch Casing, of which the following is a specification, reference being had to the accompanying drawings, forming part thereof.

The figure is a perspective view of the lock or latch casing embodying my new design.

I claim:

The ornamental design for a lock or latch casing, as shown.

WILLIAM R. FERRY.
